UNITED STATES PATENT OFFICE.

GEORGE WILKINSON, OF HARROGATE, ENGLAND.

COAL-FIRED BOILER-FURNACE.

1,296,247.

Specification of Letters Patent.

Patented Mar. 4, 1919.

Application filed May 14, 1917. Serial No. 168,456.

To all whom it may concern:

Be it known that I, GEORGE WILKINSON, a subject of the King of Great Britain, residing at Harrogate, in the county of York, England, have invented certain new and useful Improvements in Coal-Fired Boiler-Furnaces, of which the following is a specification.

This invention relates to boilers provided with coke burning grates; and it consists in combining with the boiler and its furnace, a retort for distilling coal, and arranging the retort as hereinafter fully described and claimed so that the residual coke from the retort will be automatically fed onto the boiler grate, and so that the retort will also be heated by the products of combustion formed by the coke burned on the grate.

In the drawings, Figure 1 is a vertical section through a retort, a boiler and a boiler furnace constructed according to this invention. Fig. 2 is a plan view of the same, partially in section on the line 1—1 in Fig. 1.

The setting 30 of the boiler is provided with an inclined fire grate 49. The boiler inclosed in this setting consists of two series or banks of vertical water tubes 52, the upper ends of which are connected to a steam receiver 31. The lower ends of each series of tubes are connected to a mud drum 56, and the water tubes are arranged in heating chambers 33 which communicate with the main heating chamber or furnace chamber

above the grate. A heating flue 50 is formed in the setting and is arranged at one side of the grate and the furnace chamber, and above the upper end portion of the grate.

This flue or heating chamber 50 communicates with the furnace chamber by a duct or

cross-passage 51. A retort 48 for distilling coal is arranged in the heating flue, and its lower end is arranged so that the residual coke is discharged automatically onto the upper part of the grate 49. The coke burns on the said grate and heats the water in the water tubes of the boiler, and portions of the products of combustion pass through the duct 51 into the flue 50 and heat the retort 48. The boiler may be variously constructed in carrying out this invention, and has all the necessary fittings of any approved construction.

What I claim is:

1. The combination, with a boiler furnace provided with a grate and a heating chamber for the boiler, said furnace having also a vertical heating flue arranged to one side of the grate and a lateral passage connecting the said heating chamber and flue, of a gas retort arranged in the said heating flue and operating to discharge coke automatically onto the said grate.

2. The combination, with a steam boiler and a gas retort arranged side by side, of a setting provided with separate heating chambers or flues for the said boiler and retort and having a lateral passage between the said heating chambers or flues, and a grate operating to heat both heating chambers, the said retort being arranged to discharge coke automatically onto the said grate.

In testimony whereof I affix my signature in the presence of two witnesses.

GEORGE WILKINSON.

Witnesses:

FRED. J. RATCLIFFE,
JAMES A. HINCHLEY.
